DEVICE AND METHOD FOR OPENING
CLOGGED PIPES AND THE LIKE

Raymond C. Gannon, Syracuse, N. Y.

Application April 19, 1935, Serial No. 17,344

12 Claims. (Cl. 15—269)

This invention relates to an improved device and method for opening clogged pipes and clearing obstructions therefrom. More particularly, the invention is principally designed for use in opening and clearing obstructed plumbing systems commonly used to direct sewage and other waste matter from household fixtures and the like, to the main sewer line. The clearing of such obstructions is known in the plumbing practice as breaking the seal of a trap.

Various ways and means of freeing or clearing stoppages in the sewer lateral have been employed, but for the most part, they are attended by considerable expense. One of the most common expedients employed in the case of stoppage is to apply a high pressure to the lateral as by connecting a hose to a high pressure water main and extending the hose into the basement trap or into the vent pipe to flush or "blow out" the obstruction. If the stoppage is not too severe, this may be effective, but in the case of a severe stoppage, obviously, the high pressure will merely pack or wedge the obstruction more firmly in the pipe, and the flushing water will back up and overflow into the basement, or even higher up in the building where the fixtures are located. Reaming tools are also sometimes used, but they are difficult to handle and operate, and quite frequently the obstruction cannot be reached without digging a trench so as to expose the lateral and enable removal of a section of the pipe to permit the introduction of the reaming tool into the pipe at a point relatively close to the obstruction. This is a tedious and expensive method, especially if any trench digging is necessary.

One of the objects of my invention is to provide a simple and inexpensive device which is effective to open or clear clogged sewer systems of the type hereinbefore referred to, and which may be employed to accomplish the desired results without disturbing the plumbing connections or requiring trench digging.

Another object of the invention is to provide a plunger-like device which is adapted to be introduced into the vent pipe and/or the basement trap pipe and reciprocated upwardly and downwardly so as to clear these pipes and/or the sewer lateral of obstructions.

A still further object of the invention is to provide a plunger device for use in the above mentioned manner, the plunger being of a unique and improved construction whereby an effective and peculiar agitation action is imparted to the waste water or fluid trapped in the system, which action tends to loosen the obstructing matter and

eventually free the same so that it will be carried off and discharged with the waste liquid.

A still further object of the invention is to provide a plunger device which, when reciprocated in the vent or basement trap pipe, concentrates the pressure exerted by the plunger on successively changed areas of the waste fluid, whereby the latter is agitated with a variously changing motion during continued reciprocation of the plunger.

The invention also contemplates a new method of freeing clogged sewer systems and the like, which method embraces generally the creation of a swirling or eddying motion of the liquid trapped in the system and changing the swirling motion so as to be effective in different portions of the liquid to gradually loosen the obstructing matter.

Other and further objects and advantages of the invention will be hereinafter described and the novel features thereof defined by the appended claims.

In the drawing:

Fig. 1 is a diagrammatic view of a conventional plumbing installation frequently employed for handling waste water and sewage in dwellings or other buildings, and illustrating the new method of freeing the system from obstructions tending to clog the same;

Fig. 2 is a detail view partly in section, of the improved plunger device which has been developed to practice the new method herein;

Fig. 3 is a sectional view taken approximately on the line 3—3 of Fig. 2; and

Fig. 4 is a fragmentary detail sectional view further illustrating the use of the improved plunger device.

Like reference characters designate corresponding parts in the several figures of the drawing.

Referring first to Fig. 1, the waste or sewage system embodies a sewer lateral 1, which, as shown, is usually buried in the ground beneath the basement floor. This lateral extends from the building out to the street, where it connects with the usual sewer main (not shown). Within the building, and running vertically therethrough, is the soil pipe or stack 2, to which the waste lines of the usual plumbing fixtures are connected. The lower end of the stack or soil pipe 50 is connected with the sewer lateral 1 in any suitable manner, as for example, by means of a Y coupling 3. At some point intermediate the building and the street, is located a vent pipe 4, the lower end of which is connected to the lat- 55

eral 1, and the upper end of which projects slightly above the sidewalk or street level. The vent 4 is usually provided with a guard or cover 5 of such construction that the upper end of 5 the pipe is open to atmosphere. Adjacent the lower end of the vent pipe 4, is usually located a running trap 6, having substantially the form as shown, and providing a liquid seal at this point in the lateral 1. When a basement trap 10 is employed, it is connected with the sewer lateral 1, so that the stack 2 is disposed between the basement trap and the vent 4. The basement trap is designated 7, and embodies a P trap 8, the end of which is connected to one branch 15 of the Y coupling at the junction of the soil pipe or stack with the sewer lateral 1. As shown, the basement trap extends upwardly to the basement floor level, at which point it is open to atmosphere.

20 Passing now to the device which has been developed for opening or clearing obstructions from the system described above, and referring particularly to Figs. 2 and 3 of the drawing, the device comprises an operating rod or handle 25 member 9 of suitable length, the lower end of which carries a plunger-like head, generally designated 10. This head is of novel construction and includes a suitable abutment 11, which may have the form of a nut threaded on the lower 30 end of the operating member 9. Next to the abutment 11 is positioned a rigid bearing member 12 having the form of a metal washer or disc. A flexible sealing member 13 is mounted on the operating member 9 below the bearing member 35 12, and this sealing member is provided with a central opening 14, which opening is substantially larger than the end of the operating member for purposes which will hereinafter become more apparent. The sealing member or washer 40 13 is preferably made of leather, although the same may be formed from other materials, such as rubber, cork composition, or other similar materials of a suitable degree of flexibility or yieldability. Associated with the sealing member 45 13 is a bearing member 15 which comprises a rigid disc-like washer having a size approximating the size of the pipe into which the plunger device is to be introduced. For the best results, this bearing member 15 is just slightly smaller 50 than the internal size of the pipe, and the same is provided with an opening 16 substantially larger than the size of the operating member, and through which the operating member extends. Another bearing member or washer 17, 55 similar to bearing member 12, is mounted on the operating member next to the member 15, and all of the bearing members and the sealing member 13 are retained in position on the end of the operating member by means of a nut or 60 cap 18 threaded onto the end of the operating member. In practice, the nut or cap 18 is screwed onto the operating member to an extent sufficient to exert a slight clamping pressure on the parts between the nut 18 and the abutment 11. 65 However, I prefer to keep this clamping pressure very slight, so as to permit lateral movement of the sealing member 13 and the bearing member 15 respecting the operating member. Likewise, these latter parts are permitted to rotate on the operating member.

70 As shown, the sealing member 13 is just slightly smaller in size than the bearing member 15, and in adjusting these parts to obtain the desired results, the sealing member 13 is disposed 75 slightly off center so that it will project beyond

the outer edge of the bearing member 15, as at 19. This adjustment is permitted by reason of the openings 14 and 16. The eccentric or off-center relation of the sealing member 13 and the bearing member 15 establishes a laterally 5 projecting sealing edge extending for a distance about the plunger less than the total circumference of the same, and of course, less than the internal circumference of the pipe into which the plunger device is introduced.

10 Passing now to the operation of the plunger device, when a stoppage occurs in the sewer lateral, I have found that the same can be freed by introducing the plunger-like device described above into the vent pipe 4, as shown dotted in Fig. 15 1, and reciprocating the plunger head upwardly and downwardly below the surface of the fluid trapped in the system. During the reciprocation, the projecting edge 19 of the sealing member is kept against the inner wall of the pipe as 20 much as possible. However, as the operating member is moved upwardly and downwardly, the sealing member 13 and the bearing member 15 will automatically shift from time to time respecting the operating member, this shifting 25 movement including a rotating movement or a lateral movement, or both. In other words, by maintaining only a slight clamping pressure on the parts 12, 13, 15, and 17, the parts 13 and 15 are free to move at will in the manner above 30 described, and this movement takes place automatically and without any special attention of the operator. During this movement, however, the eccentric or off-center adjustment of the parts 13 and 15 is maintained, as it has been 35 found that the friction between these members is sufficient to maintain the original eccentric adjustment even though the clamping action exerted on these parts is very slight. By reason of the automatic rotation of the plunger-like head, and/or the lateral shifting of the same, respecting the operating member, the position of the pressure application exerted on the trapped fluid is changed from time to time to different 40 portions of the fluid, as the plunger-like device is 45 reciprocated. This, together with the fact that the plunger head does not completely fill the pipe, creates a peculiar agitating motion in the fluid trapped in the system, which motion is in the 50 nature of a swirling or eddying motion the position of which is varied from time to time, so as to be more or less concentrated in successively changing directions and in different portions of the fluid. The action is quite different from that 55 performed by a plunger which completely fills the pipe, and I have found in actual practice that the improved construction described herein is considerably more efficient and will free obstructions 60 which cannot be cleared by a tight-fitting plunger.

65 In Fig. 4, I have endeavored to illustrate by the arrows how the motion imparted to the trapped liquid by movement of the plunger head in a downward direction causes the liquid to impinge upon the obstructing accumulation 20, reversing its motion, and this alternate impingement and reversal of the motion gradually loosens the obstructing matter as the reciprocation of the plunger head takes place. It will be observed 70 that the cross sectional area of the trapped liquid acted upon directly by the plunger head is less than the total cross-sectional area of the body of liquid trapped in the pipe, inasmuch as the plunger head is slightly smaller than the pipe. The pressure on the liquid is thus more or less 75

concentrated toward that side of the pipe against which the flexible sealing member 13 bears, while the plunger head is slightly spaced from the opposite side of the pipe, leaving the liquid free over a portion of the cross-sectional area thereof. The free area, being rather small, causes the swirling or eddying motion of the liquid to attain a relatively high velocity as the liquid passes back and forth between the plunger head and the portion of the pipe wall which is slightly spaced therefrom, thus contributing further to the effectiveness of the loosening action of the liquid on the accumulated obstruction.

Since the plunger head is loosely mounted on the operating member or handle, so as to be free to shift laterally or rotatively relative to the handle, continued reciprocation of the head results in an automatic shifting of the position of the head and consequently an automatic changing of the position of the pressure application on the liquid area and a corresponding shifting of the swirling or eddying motion to different portions of the body of the liquid. This changing or varying of the motion of the liquid just referred to materially contributes to the effectiveness of the action of the plunger head so that the accumulation is loosened or broken up gradually that is, a little at a time.

It is to be understood that the position of the obstruction or accumulation 20, shown in Fig. 4, has been illustrated only as one example of a typical stoppage in the system. Of course, the matter may collect higher up in the vent pipe or the basement trap, as the case may be, or somewhere in the lateral 1 itself, some distance from the juncture of the vent pipe or the basement trap with the lateral. However, the action of the plunger head on the trapped fluid and the action of the latter on the accumulated matter would be substantially the same as just described although the paths of the swirling or eddying fluid would be somewhat longer and possibly more irregular than illustrated.

As hereinbefore stated, the plunger head is submerged below the level of the liquid in the vent pipe 4 and reciprocated upwardly and downwardly until the obstruction in the lateral is cleared. During the operation, the liquid level in the system will drop, and as this occurs, the plunger is lowered to keep the plunger-like head below the surface and until the clearing has been completely effected. Eventually, dislodging of the obstructing matter will take place and the trapped fluid will pass out with a rushing motion, carrying with it the obstructing matter which has been loosened by the agitation effected by the plunger.

In describing the above operation, reference has been made to the reciprocation of the plunger device in the vent pipe 4, but it is understood that its use is not confined to the vent pipe alone, as sometimes the obstruction may be cleared by reciprocating the plunger in the basement trap pipe 7. The particular location of the obstruction will sometimes make it desirable to work the plunger in the sewer trap pipe, but ordinarily, it has been found that the obstruction can be cleared by working the same in the vent pipe.

The cap or nut 18 constitutes a protuberant part disposed in advance of the plunger head. Accordingly, as the plunger works closer and closer to the bottom of the vent pipe or the basement trap pipe, the protuberant part will strike bottom first and minimize the likelihood of

damaging the plunger head. Also the protuberance may be used to break up or dislodge the obstructions which may be directly reached by the plunger, and without damaging the plunger head, as might be the case where the head was located at the extreme lower end of the operating member.

While the specific details of construction have been herein shown and described, the invention is not confined thereto, as changes and alterations may be made without departing from the spirit thereof as defined by the appended claims.

Having thus described my invention, what I claim as new and desire to secure by Letters Patent, is—

1. A plunger adapted for reciprocation within a pipe of a sewer system or the like to dislodge matter clogging the same, said plunger comprising an operating rod, a plunger head carried by said operating rod adjacent one end thereof and including a rigid disc-like member having a diameter slightly less than the internal diameter of the pipe, and a flexible sealing member adjacent said rigid disc-like member, said flexible member projecting laterally slightly beyond said rigid disc-like member for a fractional part of the circumferential distance only about the latter.

2. A plunger adapted for reciprocation within a pipe of a sewer system or the like to dislodge matter clogging the same, said plunger comprising a handle member, a plunger head carried by said handle member adjacent one end thereof and including a rigid disc-like member having a diameter slightly less than the internal diameter of the pipe, and a flexible sealing member adjacent said rigid disc-like member, said flexible member projecting laterally slightly beyond said rigid disc-like member for a fractional part of the circumferential distance about the latter, said rigid member and flexible member being loosely mounted on the handle member so as to afford relative movement between the handle member and the other members in a plane generally transverse to the handle.

3. A plunger adapted for reciprocation within a pipe of a sewer system or the like to dislodge matter clogging the same, said plunger comprising a handle member, a plunger head carried by said handle member adjacent one end thereof and including a rigid disc-like member having a diameter slightly less than the internal diameter of the pipe, and a flexible sealing member adjacent said rigid disc-like member, said flexible member projecting laterally slightly beyond said rigid disc-like member for a fractional part of the circumferential distance about the latter, said rigid member and flexible member being loosely mounted on the handle member so as to afford relative rotative movement between the handle member and the other members.

4. A device of the class described, comprising a handle member having an abutment shoulder adjacent one end, a rigid bearing member carried by said handle member and abutting said shoulder, a second rigid bearing member having a substantially larger bearing surface than the first bearing member, a flexible member interposed between said bearing members and extending beyond the edge of said second bearing member at one side thereof only, and means coacting with said abutment shoulder for exerting a limited clamping pressure on said bearing members and flexible member.

5. A device of the class described, comprising

- a handle member having an abutment shoulder adjacent one end, a rigid bearing member carried by said handle member and abutting said shoulder, a second rigid bearing member having a substantially larger bearing surface than the first bearing member, a flexible member interposed between said bearing members and extending beyond the edge of said second bearing member at one side thereof only, and means coacting with said abutment shoulder for exerting a limited clamping pressure on said bearing members and flexible member, said last mentioned means constituting a protuberant extension on the side of said bearing and flexible members opposite to the handle member.
6. A device of the class described, comprising a handle member having an abutment shoulder adjacent one end, a rigid disc-like bearing member carried by said handle member and abutting said shoulder, a second rigid disc-like bearing member having a substantially larger bearing surface than the first mentioned bearing member and of a diameter slightly less than the internal diameter of the usual sewer lateral vent pipe, said latter bearing member being carried by said handle member so as to permit lateral movement of the same respecting the said handle member, a flexible disc-like member interposed between said bearing members and disposed eccentrically respecting said second mentioned bearing member so as to project slightly beyond the edge of the latter for a distance thereabout which is less than the total circumferential distance around the same, and also mounted so as to permit lateral movement of the same respecting the handle member, and means coacting with the abutment shoulder for exerting a limited clamping pressure on said bearing members and flexible member.
7. A device of the class described, comprising a handle member having an abutment shoulder adjacent one end, a rigid disc-like bearing member carried by said handle member and abutting said shoulder, a second rigid disc-like bearing member having a substantially larger bearing surface than the first mentioned bearing member and of a diameter slightly less than the internal diameter of the usual sewer lateral vent pipe, said latter bearing member being carried by said handle member so as to permit lateral movement of the same respecting the said handle member, a flexible disc-like member interposed between said bearing members and disposed eccentrically respecting said second mentioned bearing member so as to project slightly beyond the edge of the latter for a distance thereabout which is less than substantially one-half of the total circumferential distance around the same, and also mounted so as to permit lateral movement of the same respecting the handle member, and means coacting with the abutment shoulder for exerting a limited clamping pressure on said bearing members and flexible member.
8. A device of the class described, comprising a handle member having an abutment shoulder adjacent one end, a rigid disc-like bearing member carried by said handle member and abutting said shoulder, a second rigid disc-like bearing member having a substantially larger bearing surface than the first mentioned bearing member and of a diameter slightly less than the internal diameter of the usual sewer lateral vent pipe, said latter

bearing member being carried by said handle member so as to permit lateral movement of the same respecting the said handle member, a flexible disc-like member interposed between said bearing members and disposed eccentrically respecting said second mentioned bearing member so as to project slightly beyond the edge of the latter for a distance thereabout which is less than the total circumferential distance around the same, said flexible member being mounted on said operating member so as to permit lateral movement of the same respecting said handle member, and means coacting with said abutment shoulder for exerting a clamping pressure on said second bearing member and flexible member sufficient to maintain the eccentric relation between the flexible member and said second mentioned bearing member while permitting lateral movement of each of the same during reciprocation of the device within the pipe aforesaid.

9. The method of clearing a clogged sewer pipe containing an appreciable body of liquid trapped in the area to be cleared, comprising applying axial pressure in one direction to an appreciable cross-sectional area only of the trapped liquid, whereby a portion of said liquid moves in that general direction and some of the liquid also moves generally in the reverse direction in the other portion of the cross-sectional area, so that a swirling or eddying motion of the liquid, impinging on the obstruction, is produced.

10. The method of clearing a clogged sewer pipe containing an appreciable body of liquid trapped in the area to be cleared, comprising alternately applying axial pressure in rapidly reversed directions to an appreciable cross-sectional area only of the trapped liquid, whereby a portion of said liquid moves in that general direction, and some of the liquid also moves generally in the reverse direction in the other portion of the cross-sectional area, so that a swirling or eddying motion of the liquid, impinging on the obstruction, is produced.

11. The method of clearing a clogged sewer pipe containing an appreciable body of liquid trapped in the area to be cleared, comprising applying axial pressure in one direction to an appreciable cross-sectional area only of the trapped liquid, whereby a portion of said liquid moves in that general direction, and some of the liquid also moves generally in the reverse direction in the other portion of the cross-sectional area, so that a swirling or eddying motion of the liquid, impinging on the obstruction, is produced, and varying the position of the pressure application aforesaid on the cross-sectional area of the trapped liquid around the pipe.

12. The method of clearing a clogged sewer pipe containing an appreciable body of liquid trapped in the area to be cleared, comprising applying axial pressure in one direction to an appreciable cross-sectional area only of the liquid, while leaving a relatively small area of the liquid free, whereby a portion of said liquid moves in that general direction and some of the liquid also moves generally in the reverse direction in the free portion of the cross-sectional area and at a relatively high velocity so that a swirling or eddying motion, impinging on the obstruction, is produced.

RAYMOND C. GANNON.
